UNITED STATES PATENT OFFICE.

JOHN N. HARSON, OF NEW HAVEN, CONNECTICUT, ASSIGNOR TO M. JOSEPH HARSON, OF PROVIDENCE, RHODE ISLAND.

HAT-SWEAT.

SPECIFICATION forming part of Letters Patent No. 326,081, dated September 8, 1885.

Application filed November 17, 1884. (No model.)

To all whom it may concern:

Be it known that I, JOHN N. HARSON, of New Haven, in the county of New Haven and State of Connecticut, have invented a new 5 Improvement in Hat-Sweats; and I do hereby declare the following, when taken in connection with accompanying drawings, and the letters of reference marked thereon, to be a full, clear, and exact description of the same, 10 and which said drawings constitute part of this specification, and represent, in—

Figure 1, a perspective view showing the sweat in the hat; Fig. 2, a vertical section of the hat; Fig. 3, a vertical section, enlarged, 15 showing the sweat contracted.

This invention relates to an improvement in the leather lining arranged around the inside of a hat at the brim to protect the hat from perspiration, &c., and commonly called 20 the "sweat."

In that class of hats in which the brim and crown are stiff or hard, in contradistinction to what are commonly called "soft" hats, great difficulty is experienced in properly fitting 25 the hat to the wearer, reliance being had on a block shaping or conformation; but this will not adapt the hat to many irregularities in shape of a head. The sweats are vertical, so that a substantial bearing upon the head only 30 comes around the opening at the bottom of the sweat. Many times a filling is introduced inside the sweat to contract its upper edge and give to it a cushion-like shape or effect upon the head, but this filling only increases the 35 thickness around the head to the discomfort of the wearer.

The object of my invention is to construct the sweat so that it may be in itself shaped to conform to the shape of the head or adapt 40 it to the comfort of the wearer; and it consists in cutting a V-shaped vertical slit at one or more points in the sweat, the apex of the V at the lower edge of the sweat, and then introducing a lacing into the edges of 45 such opening, whereby the sweat may be contracted from the lower edge upward, as more fully hereinafter described.

A represents the sweat of a hat, which is

applied and secured at its lower edge around the opening in the hat in the usual manner. 50 At one or more points (preferably three) I cut a V-shaped slit, a, from near the lower edge of the sweat upward, leaving the upper edge open. The edges of this opening are provided with perforations or eyelets, and 55 through these perforations a lacing is introduced, as shown.

If the lacing be left free and the slits open, then the sweat will lie flat upon the inside of the crown of the hat in the usual manner. 60 If it be desirable to contract the sweat the lacings are drawn up accordingly to contract the openings a. This contraction will draw the upper edge of the sweat inward, as seen in Fig. 3, to conform to the shape of the head, 65 and form a cushion-like surface for the head, the contraction of the sweat leaving a space between it and the crown, as seen in Fig. 3.

Such a construction of the sweat will permit the sweat to assume the shape of the head 70 of the wearer, and thereby avoid the usually-required block-shaping. Such contraction may also to a considerable extent vary the size of the hat, so that the hat may be reduced for intermediate sizes, if desired. By thus 75 drawing the sweat inward around the head and leaving the open space between it and the crown, the hat is made much cooler for the wearer than when the sweat lies close to the crown, as in the usual construction. 80

These slits may be made at various points around the sweat; but I prefer to make them at three points, one at each side, the other at the front or rear, as indicated in Fig. 1. 85

I claim—

The herein-described improvement in hat-sweats, consisting in vertical V-shaped openings in the sweat, the edges of the openings perforated, and combined with lacings through 90 said perforations, and whereby the sweat may be contracted from its lower edge upward, substantially as described.

JOHN N. HARSON.
